United States Patent Office

Des. 187,988

Patented May 24, 1960

187,988

HEARING AID

Kenneth L. Olson and Mas Harada, Minneapolis, Minn.,
assignors to The Qualitone Company, Inc., Minneapolis,
Minn., a corporation of California

Filed Dec. 2, 1959, Ser. No. 58,528

Term of patent 14 years

(Cl. D26—14)

FIG. 1

FIG. 2

FIG. 4

FIG. 3

FIG. 5

Figure 1 is an elevational view of the hearing aid, showing our new design;

Figure 2 is an elevational view taken opposite the view of Figure 1;

Figure 3 is a view looking at Figure 1 from the right-hand side thereof;

Figure 4 is a bottom plan view; and

Figure 5 is an elevational view from the left hand side of Figure 1 or the right hand side of Figure 2. The essential features of our design reside in the portion shown in full lines.

We claim:

The ornamental design for a hearing aid, as shown and described.
